WORKING SCHEDULE OR INDICATING GUIDE

Filed June 27, 1923

Inventor:
Robert H. Harrison
by R. Clyde Grant, atty

UNITED STATES PATENT OFFICE.

ROBERT HENRY HARRISON, OF RALEIGH, NORTH CAROLINA.

WORKING SCHEDULE OR INDICATING GUIDE.

Application filed June 27, 1923. Serial No. 648,040.

To all whom it may concern:

Be it known that I, ROBERT H. HARRISON, a citizen of the United States, residing at Raleigh, in the county of Wake and State 5 of North Carolina, have invented certain new and useful Improvements in Working Schedules or Indicating Guides, of which the following is a specification.

This invention relates to certain improvements in working schedules or indicating guides, to facilitate in an efficient and accurate manner the carrying out of a predetermined series of operations, at predetermined periods of time, the device being particularly well adapted for use in connection 15 with laundry work.

Generally stated the improved device comprises a bar, strip, or the like, provided with a graduated series of markings representing, preferably, intervals of time in units of ten minutes each, sufficient in number to cover a period of twelve hours. Cooperating with this first mentioned bar or strip is a second like member also provided with corresponding graduations, the two members being slidably secured together and operating in a manner similar to a slide rule. The graduations on the first mentioned bar or strip are represented by numbers indicating 25 the different intervals of time, but the graduations on the second cooperating member are not so numbered, said graduations being adapted to cooperate with changeable indicia, representing the various steps of the 30 contemplated process, all combining to carry out the desired purpose, in a manner to be hereinafter more fully described.

The preferred embodiment of the invention is illustrated in perspective, in the accompanying drawing, parts being broken away to properly show the essential features 40 of the invention.

Referring to the drawing in detail the main portion of the device comprises a bar or strip 1 of any desired material, preferably about 36 inches long and provided on its face with a series of graduations, representing in the present instance, periods of time in units of ten minutes each, ranging 45 for example, from 6 o'clock to 6 o'clock, covering a period of twelve hours. These graduations are marked by numerals as indicated at 3, in consecutive order as shown and in the periods stated.

Cooperating with the bar 1 is a complementary bar 4, slidably connected thereto by

U-shaped yokes or straps 5. Corresponding to the graduations 2 of the bar 1, the bar 4 is likewise marked, the markings on both bars being arranged along adjacent edges 60 for obvious reasons.

Formed in the upper face of the sliding bar 4 are a series of perforations or holes 6 arranged in uniform order and in each instance, directly opposite each graduation 65 on said bar 4. These holes are for the reception of indicia carrying tags or strips 7, the indicia thereon representing the various steps of the processor series of operations to be performed, said strips 7 being adapted to 70 be shifted or moved with respect to each other as required or called for in accordance with the desired operation.

As hereinbefore stated the present device has been designed particularly for the use 75 in laundry establishments and the operation thereof will be explained in connection with this class of work, wherein it is desired to carry on certain steps for a certain length of time with certain intervals. Assuming 80 for example that the following formula or schedule is used, cold rinse 10 minutes, first suds 20 minutes, second suds 20 minutes, bleached 20 minutes, first rinse ten minutes, second rinse 10 minutes, sour 10 minutes, 85 blue ten minutes, the indicia will be arranged on the bar 4 as shown in the drawing, where said graduations indicate five minute intervals. The corresponding graduations on bar 1 are also arranged in 90 5 minute intervals, but it is only necessary to mark every other one or each 10 minute period of time.

If the operation is to begin at 1.30, the bar 4 is moved along until the indicia for 95 the first operation is opposite the graduation 1.30 on the bar 1, whereupon the time for each succeeding step will be represented on bar 1 as shown. Of course if the operation is to begin at some other time, it 100 is only necessary to slide the bar 4 along bar 1 until the initial step is opposite the desired period of time, the time for the following steps being indicated in a manner as hereinbefore described.

From the foregoing it will be apparent 105 that various predetermined formulas or steps of a certain process or operation can be arranged on the bar 4 in any sequence or order as desired, properly spaced to give 110 the required interval of time between each step, so that when said bar 4 is associated

with the bar 1, and by placing the initial step opposite the indicated time for beginning the operation, the time for changing or performing each successive step of the process will be automatically indicated on the bar 1.

Although the invention has been illustrated and described in connection with a laundry or washing operation, it is not to be so limited, as it will of course be perfectly obvious, that the same is applicable in its use to any operation involving a series of steps of the like nature.

What I claim is:

- 15 1. In a working guide or schedule, the combination with a main portion, of a supplemental portion associated therewith, graduations on said main portion, means for interchangeably arranging indicia on said supplemental portion in spaced relation in the desired combination, said spacings following a unit of measurement according to the graduations on said main portion and means for obtaining a cooperating reading between said portions.
- 20 2. In a working guide or schedule, the combination with a main portion, of a supplemental portion associated therewith, graduations on said main portion, indicia carrying strips supported upon said supplemental portions, means for interchangeably arranging said strips thereon in spaced relation in the desired combinations, said spacings following a unit of measurement according to the graduations on said main portion and means for obtaining a cooperating reading between said portions.
- 25 3. In a working guide or schedule, the combination with a main portion, of a supplemental portion associated therewith,

graduations on said main portion, corresponding graduations on said supplemental portion, indicia carrying strips, means for securing said strips to the supplemental portions in spaced relation in the 45 desired combinations, and means for obtaining a cooperating reading between said portions.

4. In a working guide or schedule, the combination with a main portion, of a supplemental portion associated therewith, graduations on said main portion, corresponding graduations on said supplemental portion, holes formed in the supplemental portion opposite each graduation, indicia 55 carrying strips, pins passing through the strips into said holes for securing the strips to the supplemental portion in spaced relation in the desired combination, and means for obtaining a cooperating reading between 60 said portions.

5. In a working guide or schedule, the combination with a main bar or rod, of a supplemental bar associated therewith, graduations on said main bar, numerals 65 representing regular periods of time designating said graduations, corresponding graduations on said supplemental bar, holes formed in the supplemental bar opposite each of said latter graduations, indicia 70 carrying strips, pins passing through the strips into said holes for securing the strips to the supplemental bar in spaced relation in the desired combination, and means for causing a close sliding engagement between 75 said bars to obtain a cooperating reading thereby.

In testimony whereof I affix my signature.

ROBERT HENRY HARRISON.
